HANDBAG SNAP LOCK

David Damast, 522 Shore Road,
Long Beach, N.Y. 11561

Filed May 7, 1968, Ser. No. 11,809

Term of patent 3½ years

Int. Cl. D8—03

U.S. Cl. D87—2

FIG. 2 is an assembled top plan view thereof;

FIG. 3 is a front view thereof; and

FIG. 4 is a side elevational view thereof.

I claim:

The ornamental design for a handbag snap lock, substantially as shown.
